(57) **CLAIM**

The ornamental design for a chair, as shown and described.

DESCRIPTION

FIG. 1 is a perspective view of a chair;

FIG. 2 is a front view thereof;

FIG. 3 is a right view thereof;

FIG. 4 is a back view thereof;

FIG. 5 is a left view thereof;

FIG. 6 is a top view thereof; and,

FIG. 7 is a bottom view thereof.

Various figures are illustrated with various grayscale levels of surface shading to show various contrasting appearances of different portions of this design. No particular color or design pattern is claimed.

1 Claim, 7 Drawing Sheets
